UNITED STATES PATENT OFFICE.

WILLIAM Y. THOMAS, OF WEST PITTSTON, PENNSYLVANIA, ASSIGNOR OF
ONE-THIRD TO WILLARD B. CULVER, OF SAME PLACE.

LUBRICATOR.

SPECIFICATION forming part of Letters Patent No. 325,578, dated September 1, 1885.

Application filed February 14, 1885. (No model.)

To all whom it may concern:

Be it known that I, WILLIAM Y. THOMAS, a citizen of the United States, residing at West Pittston, in the county of Luzerne, State of Pennsylvania, have invented a new and useful Improvement in Lubricators, which improvement is fully set forth in the following specification and accompanying drawings, in which—

10 Figure 1 represents a top or plan view of a lubricator embodying my invention. Fig. 2 represents a section thereof in line *xx*, Fig. 1, and a section of a shaft or journal and portion of a pulley or wheel thereon.

15 Similar letters of reference indicate corresponding parts in the two figures.

My invention consists of a lubricator attachable to a pulley, wheel, roller, &c., and provided with means whereby the centrifugal 20 action is employed to direct the oils to the duct leading to the journal or axle.

Referring to the drawings, A represents a journal or shaft, and B represents a pulley, wheel, roller, &c., rotating thereon, said pulley having a duct, C, which receives the oil-discharging tube D of the lubricator E, and leads to the surface of the journal A, so that the oil from the lubricator is directed to said journal.

30 The lubricator E consists of a casing or box provided with an inlet or supply nozzle, F, and the discharge or conveying tube D above referred to. The bottom G of the casing is bent upwardly in inverted-V shape, so that the tube D joins the rise of the bottom at the center thereof.

Within the casing is a deflector, H, which consists of a plate hinged or pivoted at one end to the bottom or sides of the casing and 40 located above or overhanging the top of the tube D, so as to open and close the same. The deflector is adjusted by a screw, J, which is inserted in the top or cap of the casing and secured by a jam-nut, K.

45 It will be seen that when the pulley rotates in the direction of the arrow the oil in the chamber of the casing on the left side thereof

is directed by a centrifugal action up the inclined portion of the bottom of the casing and crowded against the free end of the deflector H, thus lifting the same and opening the top of the tube D, so that the oil is positively directed into said tube, and so passed through the duct C to the journal to be lubricated, it being seen that the feed of the oil may be regulated with the greatest nicety, and the tendency of the oil to be driven by centrifugal action against the cap of the casing and thus away from the top of the tube is prevented, owing to the deflector H, which is located as it is between the cap and bottom of the casing and held as a stop at one end by its hinge or pivot over the tube D, so as to guide the oil to the top of said tube, as has been stated.

As the bottom of the casing is raised from each side to the center, two chambers are formed in said casing, so that a large supply of oil may be provided in the casing, and the oil passes from the right to the left chamber through the space above the deflector during the rotation of the pulley, whereby the left chamber is replenished. When the lubricator stands upright to any extent or above the center of the pulley, the deflector closes on the tube D and prevents the oil from leaving the casing.

Having thus described my invention, what I claim as new, and desire to secure by Letters Patent, is—

1. A lubricator consisting of a casing attachable to a rotating device having a deflector within the same whereby, by centrifugal action, the oil is directed by the deflector to the discharge-pipe or outlet of the casing and thus to the journal or shaft to be lubricated, substantially as and for the purpose set forth.

2. A lubricator having a casing which is formed with a bottom bent upwardly, and provided with a discharge-tube communicating with said casing at the upper end of said bottom, substantially as and for the purpose set forth.

3. A lubricator having a casing provided

with a discharge-pipe and a deflector within the casing overhanging the pipe, substantially as and for the purpose set forth.

4. A lubricator having a discharge-pipe, a movable deflector within the same, and an adjusting-screw for said deflector, substantially as and for the purpose set forth.

5. In a lubricator, a casing having a dis-

charge-tube, a deflector over the entrance end of said tube, an adjusting-screw for said deflector, and a jam-nut for said screw, substantially as and for the purpose set forth.

WM. Y. THOMAS.
